CLAIM

The ornamental design for a toilet paper holder with storage, as shown and described.

DESCRIPTION

FIG. 1 is a front elevation view of a toilet paper holder with storage;

FIG. 2 is a right side elevation view thereof;

FIG. 3 is a back elevation view thereof;

FIG. 4 is a top plan view thereof;

FIG. 5 is a first bottom perspective view thereof;

FIG. 6 is a left side elevation view thereof;

FIG. 7 is a top perspective view thereof; and,

FIG. 8 is a second bottom perspective view thereof.

The broken lines shown in FIG. 3 illustrate portions of the toilet paper holder with storage and form no part of the claimed design.

1 Claim, 8 Drawing Sheets
